PACKAGING TRAY FOR FOOD PRODUCTS

William M. Miller, Jr., and Benton Neal Harris, Baltimore, Md., assignors to Gulf States Paper Corporation, Tuscaloosa, Ala., a corporation of Delaware

Filed Mar. 7, 1963, Ser. No. 73,876

Term of patent 14 years

(Cl. D58—12.6)

FIG. 1

FIG. 2

FIG. 3

FIGURE 1 is a top plan view of a packaging tray for food products showing our new design;

FIGURE 2 is a side elevation thereof, the opposite side being the same in appearance; and

FIGURE 3 is a cross-sectional view on line 3—3 of FIGURE 1.

The characteristic features of our design reside in a shallow rectangular tray having a flange around the top edge with rounded corners on the inside and having concentric raised oval ribs running on the longitudinal axis of the bottom thereof, all as shown.

We claim:

The ornamental design for a packaging tray for food products, as shown and described.
